ELECTRIC HAIR CLIPPER

William M. Walton and John F. Wahl, Sterling, Ill., assignors to Wahl Clipper Corporation, Sterling, Ill., a corporation of Illinois

Filed Oct. 15, 1969, Ser. No. 19,582

Term of patent 14 years

Int. Cl. D28—03

U.S. Cl. D95—3

FIG. 1 is a top perspective view of an electric hair clipper showing our new design;

FIG. 2 is a bottom plan view;

FIG. 3 is a front elevational view;

FIG. 4 is a left side elevational view;

FIG. 5 is a right side elevational view;

FIG. 6 is a rear elevational view;

FIG. 7 is a schematic sectional view on line 7—7 of FIG. 5;

FIG. 8 is a schematic sectional view on line 8—8 of FIG. 2;

FIG. 9 is a schematic sectional view on line 9—9 of FIG. 2; and

FIG. 10 is a schematic sectional view on line 10—10 of FIG. 2.

The power cord is shown fragmentarily in FIGS. 1, 2, 4, 5 and 6 for convenience of illustration.

We claim:

The ornamental design for an electric hair clipper, as shown and described.
